H. G. GILLMOR.
RAIL ANCHOR.
APPLICATION FILED OCT. 12, 1916.

1,358,726.

Patented Nov. 16, 1920.

UNITED STATES PATENT OFFICE.

HORATIO G. GILLMOR, OF WASHINGTON, DISTRICT OF COLUMBIA.

RAIL-ANCHOR.

1,358,726.

Specification of Letters Patent. Patented Nov. 16, 1920.

Application filed October 12, 1916. Serial No. 125,184.

To all whom it may concern:

Be it known that I, HORATIO G. GILLMOR, a citizen of the United States, residing at Washington, in the District of Columbia, have invented a new and useful Improvement in Rail-Anchors, of which the following is a specification accompanied by drawings.

My invention relates to devices known as rail anchors, rail stays or anticreepers, and one of its objects is to provide a simple device which will prevent the longitudinal movement of the rails of railways generally designated as "creeping" of the rails.

10 A further object of the invention is to provide a two piece device, in which one of the parts may be made by the bending of a rolled bar cut to the proper length.

15 A further object of the invention is to provide a device; which, while it grips both sides of the rail base and both edges thereof, may be applied to rails which vary somewhat in the dimensions of the base flange.

20 A further object of the invention is to provide a device which cannot be loosened or detached from the rail by reverse movement of the rail, changes in temperature, vibration or other accidental cause.

25 One embodiment of the invention is illustrated in the accompanying drawings, in which:—

Figure 1 is an elevation, looking toward the tie, with the rail in section, showing the device in operative position.

30 Fig. 2 is an elevation, looking away from the tie, with the rail in section, showing one of the positions of the parts while being applied to the rail.

35 Fig. 3 is a plan view looking down upon the rail, showing the device in operative position.

40 Fig. 4 is a larger view of the pressure producing part.

Fig. 5 is a view of one end of the bottom 45 of the transverse part of the device, looking up.

Similar letters refer to similar parts throughout the several views.

In the embodiment of the invention illustrated in the drawings, A represents the rail having a base flange B of the usual type resting upon and supported by the tie or sleeper C which is embedded in the ballast material and, therefore, a fixed part of the road bed. The rail anchor has two parts, the transverse member D and the pressure

producing part E. The transverse member D is provided with an arm or jaw F, which engages the rail base flange B at one side of the rail; and, at the other end, of the member D there are portions G and H, which are constructed to engage the opposite edge of the rail base B and are connected to the body portion of the member D by portions I and K. On the lower portion of the member D, adjacent the portions G and H there is a seat or bearing L, and, between the two ends of the transverse member D, there is formed a tie-engaging flange M. The portions N and O of the portions G and H of the member D, which engage directly with the rail base flange B, may be made of such form that they will upset or deform when pressure in excess of a designed limiting pressure is brought upon them. To facilitate the application of the device the transverse portion of the member D may be initially curved or inclined downward as indicated at P in Fig. 2.

The pressure producing part E is formed 80 of steel bar bent to the curve Q at its upper portion so that the end cut R of this end of the bar will form a surface adapted to engage, when the part is in position, the upper surface of the base flange B of the rail A 85 and to the curve S at its lower portion, so that there will be formed on this portion the surface T, which, when the part is in place, will engage the seat or bearing L of the transverse member D.

90 The device is applied to the rail by placing the member D with the jaw F engaging the rail base flange B at one side of the rail and then driving the member D transversely until the portions N and O will begin to engage the edge of the base flange B at the side of the rail opposite to that engaged by the jaw F. The pressure producing part E is then hooked over or engaged with the member D so that the surface T of the part E 100 engages the seat or bearing L of the member D and the upper end of the part E is brought into engagement with the corner of the base flange B. The part E can then be forcibly moved, either by the use of a suitably designed wrench or by driving, angularly, in a plane transverse to the rail. One of the positions assumed while being so moved angularly is shown in Fig. 2. During this forced angular movement of the 110 part E it will rotate about the seat or bearing L in the member D and will draw the

end of the member D upwardly with the portions N and O of the portions G and H in contact with the edge of the rail base flange B; and, if the rail base flange B is of normal width, there will be some slight flexure of the portion K which connects the portion H to the body of the member D. If, however, the width of the rail base flange B is greater than the normal width, as the end 10 of the member D is drawn up to the rail bottom by the action of the pressure producing part E, the portion K connecting the portion H to the body of the member D will be subject to greater flexure and the portion I connecting the portion G to the body of the member D will also be subjected to flexure or bending so that the distance between the portions N and O and the side of the jaw F engaging the other edge of the rail base flange B will be increased to allow for the 20 excess in width of the rail base flange B. Moreover, the portion N of the portion G of the member D is constructed so that, where the rail base B is excessively wide, this portion N will be deformed, as indicated at U in Figs. 2 and 3, to further adapt the member D to the oversize in the rail base flange B. It will readily be understood that the 25 flexure or bending of the portions I and K of the member D and the deformation, which the portion N is designed to undergo, will permit the member D to be used with rails which vary considerably in the dimension of the base flange B.

30 It will also be readily understood that the pressure producing part E may be very simply and inexpensively manufactured by bending a rolled bar of suitable length to the proper shape and that this part will, by 35 reason of its form, as well as by reason of the material of which it is formed, be resilient and especially adapted to produce and exert continuing pressure upon the rail and the member D.

40 Should the rail, for any reason, move forward, that is in the direction of the arrow in Fig. 3, the device will be carried with the rail until the tie engaging portion M of the member D is brought into full engagement 45 with the tie C. Thereafter further movement of the rail in the forward direction will be prevented by the grip of the device upon the rail and the engagement of the portion M of the member D with the fixed 50 portion of the roadbed. If the rail should move in the reverse or backward direction, even if the tie engaging portion M of the member D should be held in the ballast, the part E will hold the device securely 55 locked to the rail and the grip of the device upon the rail will not be lessened by such 60 reverse movement.

While I have described the invention as embodied in one construction, modifications 65 might be made without departure from the

principles of the invention. Therefore, I do not wish to be understood as limiting the invention to the particular construction, arrangement and devices shown and described except so far as these limitations are specifically set forth in certain of the claims herein.

I claim and desire to secure by Letters Patent:

1. A part for anticreepers constructed 75 from a rolled bar having one end bent to form an arm adapted to engage the rail above the base thereof and the other end bent to form a hook adapted so to engage a rail bottom engaging element below the rail 80 as to permit angular movement of said element about axes at right angles the one to the other.

2. A vertical pressure producing part for 85 rail anchors formed of rolled bar constructed so to engage a rail bottom engaging part below the rail that rotational movement of said pressure producing part about an axis below the rail will force a surface of said pressure producing part into engagement 90 with the upper surface of the base flange of the rail and thereby produce pressure of the bottom engaging part upon the bottom of the rail.

3. An element for anticreepers, comprising 95 a casting having, at one end, an arm adapted to engage the upper surface of the base flange of the rail at one side of the rail and, at the other end, portions adapted to engage the edge of the rail base flange at 100 the other side of the rail said edge engaging portions being connected to said element by flexible portions.

4. An anticreeper, comprising two rail gripping elements, one of which is provided 105 with means for engaging a fixed portion of the roadbed in opposition to the tendency of the rail to creep, and one of which comprises a rolled bar having one end bent to form a hook engaging rotatably with the other element below and the other end bent to form 110 an arm engaging the rail base above the rail bottom.

5. An anticreeper for rails, comprising a rail gripping element, and a part constructed 115 from a rolled bar engaging the upper surface of the rail base at one side of the rail opposite to said gripping element and so pivoted to said gripping element as to be rotatable about a longitudinal axis below 120 the rail for effecting the gripping action of said element.

6. A rail anchor, comprising a flange gripping and bottom engaging element, and a bent rolled bar adapted so to engage with 125 the rail above and said bottom engaging element below the rail base that movement of the rail in relation to said flange gripping and bottom engaging element will produce angular movement of said rolled bar and 130

thereby increase the grip of the anchor upon the rail.

7. A rail anchor, comprising a flange gripping and bottom engaging element provided with a tie engaging portion, and a bent rolled bar adapted so to engage with the rail above and said bottom engaging element below the rail base that movement of the rail in relation to said flange gripping and bottom engaging element will cant said rolled bar and thereby increase the pressure of said flange gripping and bottom engaging part upon the rail.

8. A rail anchor, comprising two rail gripping elements, one of which is provided with means for engaging a fixed portion of the roadbed in opposition to the tendency of the rail to creep, and one of which comprises a bent rolled bar engaging, at one side of the rail only, the base flange above and the other element below the rail bottom.

9. A rail anchor, comprising two rail gripping elements, one of which is formed with means for engaging a fixed portion of the roadbed in opposition to the tendency of the rails to creep and has a jaw engaging the rail base at one side and a shoulder yieldably connected to said element engaging the rail base edge at the other side of the rail, and one of which comprises an element bearing upon the top of the rail base and engaging the other element to draw and hold said element with said shoulder in engagement with the rail base edge.

10. An anticreeper, comprising two rail gripping elements, one of which is provided with a tie-abutting portion, and one of which comprises a rolled bar so bent that one end of said bar engages the upper surface of the base flange of the rail and the other end forms a hook which engages the other element and presses said other element up against the rail base.

11. A rail stay, comprising two rail engaging and gripping elements, one of which is formed with means to give the device a fixed position in the roadbed as against the tendency of the rail to creep, and one of which comprises a rolled bar which is bent to such form that it embraces one edge of the rail base and one end of the other member and clamps the rail between them.

12. An anticreeper, comprising two parts, one of which is a transverse member engaging the bottom and opposite edges of the rail base, and the other a curved rolled bar which embraces one side of the rail base and the other member and exerts pressure thereon, one of said parts being provided with tie-engaging means.

13. A rail anchor, comprising two rail gripping elements, one of which is formed with a tie-engaging flange, engages the rail base at one side of the rail, extends transversely beneath the rail and engages the

edge of the rail base at the other side of the rail with a deformable portion, and the other comprises a member which engages the element and the upper surface of the rail base and is forced into position by angular movement about said element first named.

14. A device for preventing the creeping of rails, comprising two rail gripping members, one of which is formed to engage a fixed portion of the roadbed in opposition to the tendency of the rail to creep and comprises a transverse element engaging the rail base at opposite sides of the rail, the rail base engaging portion at one side of the rail being yieldably connected to the transverse portion of said element, and the other a clamp engaging the rail base above and said element below the rail to draw and hold said element against the rail base.

15. A rail anchor, comprising two rail engaging and gripping parts, one consisting of a part embracing the base of the rail, and the other a rolled bar so curved that one end engages the rail base above and the other end forms a hook which so engages said part below the rail as to permit angular movement of said bar about said part.

16. A device for preventing the creeping of rails comprising a rolled bar bent to embrace one side of the rail base and a transverse part which engages the rail base at the other side of the rail and intervenes between the rail bottom and said bar, said transverse part having a tie-engaging portion.

17. A rail anchor, comprising a transverse element engaging the rail base at one side of the rail, a clamp constructed by bending a rolled bar which engages said element below and the base of the rail above the bottom of the rail at the other side of the rail, and tie-engaging means attached to one of said elements.

18. An anticreeper, comprising a transverse element having a jaw engaging the rail base at one side of the rail and a portion yieldably connected to said element engaging the edge of the rail base at the other side of the rail, and a pressure producing part engaging the upper surface of the rail base and said element at the other side of the rail and pressing said element against the rail base, one of said elements being provided with a tie-engaging portion.

19. A rail anchor, comprising a clamp embracing the rail base at one side of the rail, and a transverse part, having a deformable portion engaging the rail base edge, which intervenes between the clamp and the rail bottom and engages the rail base at the other side of the rail and is provided with a tie-engaging flange.

20. A rail stay, comprising a resilient clamp, formed by bending a rolled bar, engaging the upper surface of the rail base at one side of the rail, and a transverse member

which intervenes between said clamp and the rail bottom and embraces the other side of the rail base and is provided with means for engaging a fixed portion of the roadbed in opposition to the tendency of the rail to creep.

21. An anticreeper, comprising a part formed at one end with an arm adapted to engage the upper surface of the base flange 10 at one side of the rail and at the other end with rail base edge engaging portions yieldably connected to the body of said part, and a bent rolled bar adapted to engage said part and the upper surface of the rail base 15 at one side of the rail, one of said elements having a tie-engaging portion.

22. An anticreeper, comprising a part formed at one end with a jaw adapted to engage the rail base at one side of the rail 20 and with a deformable edge engaging portion adapted to engage the edge of the rail base at the other side of the rail and provided with means for giving said part a fixed position in the roadbed in opposition 25 to the tendency of the rail to creep, and a clamp adapted to engage said part below and the rail base above the rail bottom at one side of the rail.

23. An anticreeper, comprising rail gripping elements, one of which has a tie abutment and portions engaging the rail base at opposite sides of the rail, those at one side of the rail being yieldably connected to said element, and one of which elements is a 35 clamp which bears against the upper surface of the rail base and said element first named and clamps the rail between said elements.

24. A rail anchor, comprising a transversely extending part engaging the edge 40 and bottom of the rail base, a vertically disposed bent rolled bar having pivotal engagement with said transversely extending part below and with the rail base above the rail bottom, and means operative upon the 45 lower end of said rolled bar to hold said lower end in opposition to the tendency of the rail to creep.

25. A device for preventing the creeping of rails, comprising a bottom engaging part 50 constructed to bear upon the bottom of the rail, a vertically disposed bent rolled bar adapted so to engage the bottom engaging part that said bar may be rotated transversely about a longitudinal axis below the 55 rail to be forced into position and, when in position, move angularly about a transverse axis and means for giving said device a fixed position in the roadbed.

26. An anticreeper for railroad rails, comprising a rail gripping element having a 60 jaw at one end and a retaining catch yieldably connected to the other end of said element and a rail engaging device for drawing said catch into engagement with the edge of 65 the rail base.

27. A device for preventing the creeping of rails, comprising a rail base gripping bottom engaging element transversely disposed in relation to the rail and a bent rolled bar so engaging the rail base and said element as to be rotatable about an axis longitudinally disposed in relation to the rail. 70

28. A rail anchor, comprising a rail base flange engaging and gripping element, and a rail engaging device, constructed by bending a rolled bar, so engaging said element below the rail as to permit angular movement of said device about a longitudinal axis and about a transverse axis. 75

29. A device for preventing the creeping of rails, comprising a rail embracing and gripping part and a rail engaging pressure producing device, constructed by bending a rolled bar, which is so connected to said part as to be rotatable about an axis longitudinally disposed and an axis transversely disposed in relation to the rail. 80

30. An anticreeper, comprising two rail gripping elements, one of which is formed with means for engaging a fixed portion of the roadbed in opposition to the tendency of the rail to creep and has a jaw engaging the rail base at one side and a portion yieldably engaging the edge of the rail base at the other side of the rail, and one of which 95 comprises means for bearing upon the top of the rail base and engaging the other element to draw and hold said element with said base edge engaging portion in engagement with edge of the rail base. 100

31. A device for preventing the creeping of rails, comprising a rail gripping element having a jaw at one end and a deformable retaining catch at the other end of said element, a rail engaging part for drawing said catch into engagement with the rail base edge, and means for giving said device a fixed position in the roadbed in opposition to the tendency of the rail to creep. 105

32. A device for preventing the creeping of rails, comprising a rail gripping element embracing the rail base flange at one side of the rail and constructed with a yielding catch projection adapted to engage the rail base flange at the other side of the rail, and 115 a rail engaging part constructed to engage said element for drawing said yielding catch projection into contact with the edge of the rail base.

33. A rail anchor, comprising a rail gripping element embracing the base flange at one side of the rail and provided with a yielding catch projection adapted to engage the rail base flange at the other side of the rail and with a tie-engaging portion, and a 120 rail engaging device pivotally engaging said element for drawing said yielding catch projection into contact with the edge of the rail base flange. 125

34. A rail anchor, comprising a rail grip- 130

ping element embracing the base flange at one side of the rail and provided with a catch projection adapted to engage the rail base flange at the other side of the rail and 5 a rail engaging device engaging said element rotatably for drawing said catch projection into contact with the edge of the rail base flange.

35. A device for preventing the creeping 10 of rails, comprising a rail gripping member transversely disposed in relation to the rail provided with a rail base flange gripping portion at one end and a deformable rail base edge engaging portion at the other 15 end thereof, a pressure producing part engaging the rail base above and said gripping member below the rail, and means for giving the device a fixed position in the roadbed as against the tendency of the rail to 20 creep.

36. An anticreeper, comprising a rail gripping member for transverse disposition beneath the rail provided with a rail base gripping portion at one end and a deformable base edge engaging portion at the other 25 end thereof, a vertical pressure producing part arranged to engage the rail base flange above and said gripping member below the rail and means for holding the lower end 30 of said vertical pressure producing part in fixed position in the roadbed in opposition to the tendency of the rail to creep.

37. An anticreeping device, comprising a rail engaging element for transverse disposition beneath the rail engaging at one side of the rail the upper surface of the base flange and having yielding engagement with the edge of the base flange at the other side of the rail, a part engaging the rail base above 40 and said element below the rail and arranged to move transversely in relation to the rail for placing in position and affecting the gripping action, and means for giving said device a fixed position in the roadbed in opposition to the tendency of the rail to 45 creep.

38. An anticreeping device, comprising a rail embracing element constructed to engage the top and bottom of the base of the 50 rail at one side of the rail and to yieldably engage the edge of the base flange at the other side thereof, a vertical pressure producing part arranged to engage the base flange above and the rail base embracing 55 element below the rail, and means operative upon the lower end of said vertical pressure producing part to hold said lower end in fixed position in the roadbed in opposition to the tendency of the rail to creep.

60 39. A device for preventing the creeping of rails, comprising a rail engaging and gripping element constructed to engage the top of the base flange of the rail at one side

and to yieldably engage the edge of the base of the rail at the other side of the rail, a 65 rail engaging part constructed to engage said gripping element below the rail to effect the gripping action, and means for giving the device a fixed position in the roadbed in opposition to the tendency of 70 the rail to creep.

40. An anticreeping device, comprising a rail engaging element transversely disposed beneath the rail engaging at one side of the rail with the upper surface of the base 75 flange and at the other side of the rail in yieldable engagement with the edge of the base flange and provided with a portion adapted to engage a fixed portion of the roadbed, and a part engaging the rail base 80 above and said element below the rail and arranged to be moved transversely in relation to the rail for placing said part in position and effecting the gripping action.

41. A device for preventing the creeping 85 of rails, comprising a rail embracing element constructed to engage the bottom of the rail and a fixed portion of the roadbed, to engage the top of the base flange at one side and to yieldably engage the edge of the 90 base flange at the other side of the rail, and a pressure producing part constructed to engage the base flange above and said element below the rail.

42. A rail anchor, comprising a rail base 95 engaging part constructed with a jaw at one end a deformable base edge engaging portion at the other end and intermediate tie-engaging portion and a bearing surface, and a rail base engaging pressure producing 100 element constructed with a bearing surface so coacting with that of said part that rotational movement of said element about said part will force said element into position and effect the gripping of the rail. 105

43. A device for preventing the creeping of rails, comprising a tie-engaging rail gripping element provided with means for yieldably engaging the rail base edge at one side of the rail, and a rail engaging part 110 engaging said element for drawing said rail base edge engaging means into contact with the rail base edge.

44. A rail anchor, comprising an element embracing the rail base at one side of the 115 rail and yieldably engaging the edge of the rail base at the other side of the rail, and a part embracing the rail base and the rail base edge engaging end of said element and gripping the rail between said part and said 120 element.

45. An anticreeper, comprising an element extending transversely beneath the rail with a tie-engaging portion and yieldably engaging the edge of the rail at the other 125 side of the rail and a part embracing the

rail base and the rail base edge engaging end of said element and gripping the rail base between said part and said element.

46. A device for preventing the creeping of rails, comprising an element embracing one side of the rail base and yieldably engaging the edge of the other side of the rail base, and a part embracing the rail base and the rail base edge engaging end of said element and pivotally engaging said element for effecting the gripping action.

47. A rail anchor, comprising an element having yielding engagement with one edge of the rail base, extending transversely underneath the rail and embracing the rail base at the other side of the rail, a part embracing the rail base and the rail base edge engaging end of said element and pivotally engaging said element for effecting the grip-

ping action, and means for engaging a fixed portion of the road bed in opposition to the tendency of the rail to creep.

48. A device for preventing the creeping of rails, comprising two rail gripping elements, one of which is formed with means for engaging a fixed portion of the roadbed in opposition to the tendency of the rail to creep and has a jaw engaging the rail base at one side of the rail and a portion engaging the edge of the rail base at the other side of the rail, and one of which comprises means for rotatably engaging the other element and for bearing upon the top of the rail base to draw and hold said element with said base edge engaging portion in engagement with the edge of the rail base.

H. G. GILLMOR.
